JOHN H. BIERMANN.

UNITED STATES PATENT OFFICE.

JOHN H. BIERMANN, OF HOBOKEN, NEW JERSEY.

DESIGN FOR A BOX.

SPECIFICATION forming part of Design No. 17,866, dated November 8, 1887.

Application filed October 6, 1887. Serial No. 251,671. Term of patent 3½ years.

To all whom it may concern:

Be it known that I, JOHN H. BIERMANN, a subject of the King of Prussia, residing at Hoboken, in the county of Hudson, in the State of New Jersey, have invented and produced a new and original Design for Boxes, of which the following is a specification, reference being had to the accompanying drawing.

This invention relates to a design for a box, as set forth in the following specification and claims, and illustrated in the accompanying illustration, which represents a perspective view of a box containing my design.

In the drawing, the letter A indicates the box-lid, and B the box-body. The lid A has upon it the representation of a flower, C. Leaves D and a stem, E, are shown near said flower. Near the corners of the lid are rosettes F. Loops G and pendants H are shown secured to the rosettes. A shield-like ornament, I, is secured to the front of the box.

What I claim as new, and desire to secure by Letters Patent, is—

1. The design for a box herein shown described, the same consisting of the cover having the flower C, the rosette F at the corners, said rosettes having loops G, and body B, with the shield-like ornament I at the front of the box.

2. The design for a box herein shown described, the same consisting of the cover having the flower C, leaves D, and six rosettes F at the cover-corners, said rosettes having loops G and pendants H, and body B, with the shield-like ornament I at the front of the box.

In testimony whereof I have herein signed my name and seal in the presence of two witnesses.

JOHN H. BIERMANN.
